UNITED STATES PATENT OFFICE

137,330

DESIGN FOR A COMBINATION WRIST WATCH AND PICTURE FRAME AND STRAP THEREFOR

Charles R. Washam, Fort Benning, Ga.

Application December 1, 1943, Serial No. 111,847

Term of patent 7 years

To all whom it may concern:

Be it known that I, Charles R. Washam, a citizen of the United States, residing at Fort Benning, in the county of Chattahoochee and State of Georgia, have invented a new, original, and ornamental Design for a Combination Wrist Watch and Picture Frame and Strap Therefor, of which the following is a specification, reference being had to the accompanying drawing, forming a part thereof.

Figure 1 is a top plan view of a combination wrist watch and picture frame and strap therefor, showing my new design.

Figure 2 is a side view looking downwardly on the full disclosure portion in Figure 1.

I claim:

The ornamental design for a combination wrist watch and picture frame and strap therefor, as shown.

CHARLES R. WASHAM.
